LATERAL FILING FOLDER

Frank D. Jonas, Oyster Bay, N. Y., assignor, by mesne assignments, to Oxford Filing Supply Co., Inc., Garden City, N. Y., a corporation of New York

Application August 30, 1956, Serial No. 42,783

Term of patent 14 years

(Cl. D59—2)

I claim:

The ornamental design for a lateral filing folder, as shown.
